UNITED STATES PATENT OFFICE.

HENRY TIMKEN, OF ST. LOUIS, MISSOURI.

VEHICLE-SPRING.

SPECIFICATION forming part of Letters Patent No. 239,406, dated March 29, 1881.

Application filed December 16, 1880. (Model.)

To all whom it may concern:

Be it known that I, HENRY TIMKEN, of the city of St. Louis, and State of Missouri, have invented a new and useful Improvement in 5 Buggy-Springs, of which the following is a full and exact description, reference being had to the annexed drawings and letters marked thereon.

The nature of my invention consists in providing quarter-elliptic buggy-springs, attached to the under side of the body near the sides, and crossing each other, and attached to the side bars at the opposite sides from which they are respectively attached to the body, with a 15 flexible metal bearing-spring to give additional elasticity to the cross or quarter-elliptic springs; and it relates to that class of springs which are quarter-elliptic and turned up at the small ends, and which are fastened to the body 20 at opposite sides from each other, and from which each is respectively fastened to the side bars.

Figure 1 is a top view of the flexible metal bearing-spring, the quarter-elliptic springs, 25 the side bars, and the gearing. Fig. 2 is an end view of the bearing-springs, the quarter-elliptic springs, and a transverse section of the body and side bars at the place where the springs are attached to them, respectively.

Letter A, in Fig. 1, is a flexible metal bearing-spring, attached at one end to the large end of the spring B, and both attached permanently to the under part of the body at one side, and the other end is attached permanently to the opposite side of the body underneath, and serves to receive the pressure of the spring B, yielding as it presses against it in proportion to its elasticity, thus giving more elasticity to the spring B than if it had a rigid and inflexible bearing-plate. The ends of this bearing-spring rest on the bearings or sills of the body, so that the bearing-spring between its ends may be free to move up and down. Of course there may be one of those bearing-springs for each quarter-elliptic spring, or 45 there may be but one for each set of quarter-elliptic springs.

B B are quarter-elliptic springs turned up at the small ends, and with their large ends attached to the bearing spring or springs A 50 A, at the under side and at one end, then running, with the bearing-springs A A, to the opposite sides of the body, crossing each other, and having their small ends attached by ordinary toggles to the side bars, C C. 55

C C are ordinary side bars of buggies, with their front ends resting on the bolster, and their rear ends resting on the hind axle.

Letter F, in Fig. 2, shows a sectional view of the body, and b b show the ends of the sills 60 or bearings to which the ends of the bearing-springs A A are attached.

d d d are screws or bolts to hold the bearing-springs A A and quarter-elliptic springs B B together, and by means of which they are 65 fastened to the body F. Of course they may be fastened together and to the body in any other permanent manner.

E E are toggles connecting the small ends of the springs to the side bars. 70

The attachment of the springs B B to opposite sides of the under portion of the body and crossing each other, and being attached to the side bars, C C, at opposite sides from which they are respectively attached to the body, is 75 old, and I lay no claim to it in this specification, neither do I lay any claim to the manner in which the springs are attached to the side bars; but

What I do claim as new, and for which I 80 ask Letters Patent to be granted me, is—

The springs B B, attached to the under side of the body of a buggy at the opposite sides to each other, and crossing each other, and attached to the side bars, C C, at opposite sides 85 from which they are respectively attached to the body, in combination with the metallic bearing-springs A A, substantially as above described, and for the purposes set forth.

HENRY TIMKEN.
